UNITED STATES PATENT OFFICE

2.415.498

HYDRAULIC MECHANISM

Jay D. Johnson, Peoria, Ill., assignor to John Deere Tractor Company, Waterloo, Iowa, a corporation of Iowa

Original application June 18, 1941, Serial No. 398,539. Divided and this application March 13, 1943, Serial No. 479,130

9 Claims. (Cl. 103—1)

1

The present invention relates generally to hydraulic mechanisms of the type used for controlling the action of hydraulic lifting cylinders, such as are used on tractor power lifts, dump trucks, and the like. This application is a division of my co-pending application, Serial No. 398,539, filed June 18, 1941 and issued February 1, 1944, as Patent No. 2,340,474.

The principal object of my invention relates generally to a novel method of supporting power lift mechanism and of supplying power thereto. More specifically, it is an object of my invention to provide a novel and improved valve and pump assembly, which is exceedingly compact but efficient and durable in operation. A further specific object relates to the provision of means for mounting the valve and pump assembly on the governor housing of a tractor, with means provided for taking power from the governor shaft to drive the pump. Still another object relates to the provision of means for venting the reservoir of the valve housing in such manner that any oil or oil vapor which tends to escape from the vent in the reservoir is conducted to the tractor governor housing.

These and other objects and advantages of my invention will be apparent to those skilled in the art after a consideration of the following description, in which reference is had to the drawings appended hereto, in which

Figure 1 is an elevational view of the valve casing of a hydraulic power lift mechanism embodying the principles of my invention, showing the manner of mounting the valve casing on the governor housing of a tractor, a portion of the casing being broken away to show some of the valve mechanism in section;

Figure 2 is a section taken along a line 2-2 in Figure 1, showing the means for venting the hydraulic reservoir;

Figure 3 is a plan view of the valve and pump mechanism, and the governor housing, a portion indicated at 3-3 in Figure 1, being shown in section in Figure 3. Figure 3 is drawn to a slightly smaller scale than are Figures 1 and 2.

Referring now to the drawings, reference numeral 5 indicates, in its entirety, a vehicle such as a tractor or the like, on which is mounted a suitable drive housing 6, in this embodiment a governor housing. The housing 6 is provided with a suitable base flange 7 secured to the vehicle 5 by bolts 8. A drive shaft 9 is disposed within the housing 6, one end of said shaft being rotatably supported in a ball bearing 10, which is carried in an end plate 11, which fits snugly over an

2

opening 12 in the end of the housing 6 and secured to the housing by bolts 13. The end plate 11 is provided with an aperture 14, through which extends the drive shaft 9 a short distance beyond the end plate 11. The shaft 9 is driven through a drive gear 15, which is rigidly mounted on the shaft by means of a suitable key 16, and is secured against axial movement by the ball bearing 10 on one side and by a snap ring 17 or other conventional means on the other side. The gear 15 meshes with an engine driven gear 18 within the vehicle body, which may be either on the crank shaft or on the camshaft of the tractor engine, or on any other suitable shaft.

15 The governor mechanism, which maintains constant the speed of the tractor engine, as is well-known to those skilled in the art, has been omitted from the drawings, since it forms no part of the present invention, and is specifically dis-

20 closed and claimed in Patent 2,159,283, granted to McCormick, May 23, 1939, but it is understood that the shaft 9 is adapted to drive the governor and/or other parts of the vehicle. For example, a shaft 19 supported in a bearing 20 in the governor housing 6 extends outwardly to drive a

25 part of the engine, such as the cooling fan.

The outer end of the governor shaft 9 is splined, as indicated at 25, to drive pumping means in the form of a pair of intermeshing pump gears 26, 27. The drive gear 26 is fixed to the shaft 9 by the splines 25 and the driven gear 27 is supported for rotation about the axis of a stub shaft 28, which is journaled at opposite ends, respectively, in recesses 29, 30 in the end plate 11 and 35 in a flat wing portion 31 of a control or valve casing, indicated generally by reference numeral 32. The gears 26, 27 are enclosed within a gear housing 35, which is annular in form, that is to say, it extends peripherally around the gears 40 in close proximity to the ends of the teeth to maintain the pressure of the pump, but is open along each side thereof. However, by virtue of the position of the gear housing 35 rigidly sandwiched in between the end plate 11 and the wing portion 31, the latter two elements serve as side walls for the pump housing. The pump housing is clamped between the end wall 11 and the wing portion 31 by means of several bolts 36, which extend through suitable aligned apertures in the assembled parts and are threaded into the end plate 11. Other bolts 37 extend through aligned openings in the wing portion 31, gear housing 35, end plate 11, and engage threaded openings 38 50 in the governor housing 6. Thus, the securing 55

bolts 36, 37 hold the assembled parts tightly together in fluid retaining relation.

The valve casing 32 comprises a generally rectangular reservoir portion 40, which lies along one side of the drive or governor housing 6, the flat wing portion 31 extending generally perpendicular to one side of the reservoir portion 40 in juxtaposition to the pump housing 35 as explained above. The flat wing portion 31 supports the reservoir portion 40 through the bolts 36, 37 on the end plate 11 and drive housing 6. No other support for the valve casing 32 is required, although such may be provided if so desired.

The reservoir portion 40 is hollow to provide a fluid reservoir 41, a branch 42 of which extends through the wing portion 31 in communication with a port 43 in the inner wall of the wing portion 31. This port 43 is disposed in register with the inlet passage 44 in the pump housing 35. The gears 26, 27 rotate in the direction indicated by the arrows in Figure 1 and trap the oil or other hydraulic fluid between the teeth of the gears and the housing 35 and carry the fluid around to the discharge passage 45 in the pump housing 35.

A port 46 is disposed in the inner face of the wing portion 31 in register with the discharge passage 45 and is connected with a high pressure duct 47 extending through the wing portion 31 inwardly to valve mechanism, indicated generally by reference numeral 50, within the valve casing 32.

Inasmuch as the valve mechanism per se forms no part of the present invention, it will be but briefly described herein, as it is fully described in the above-mentioned co-pending application of which this is a division. The high pressure discharge duct 47 extends generally horizontally and intersects a vertical bore 51 in the valve casing 32. At its upper end, the bore 51 communicates with the reservoir 41, and at its lower end below the duct 47, it opens into a cylindrical valve chamber 52, formed in an extension 53 in the bottom of the casing 32. The lower end of the valve chamber 52 is tapped to receive a reducer 54, to which a delivery tube or conduit 55 is coupled in any suitable manner. The delivery conduit 55 is extended to any suitable power unit such as a piston and cylinder (not shown). A check valve 56 of the poppet type is adapted to close upwardly against the valve seat 57 for closing off communication between the delivery conduit 55 and the vertical bore 51. The check valve 56 is urged upwardly toward a closed position by means of a light spring 58, which seats in a bore 59 in the reducer 54 and encircles a guide lug 60 on the check valve 56. The stem 61 of the check valve 56 extends upwardly through the vertical bore 51 and is received within a socket 62 in the lower end of a manually controlled piston valve, indicated in its entirety by the reference numeral 63. This manual valve comprises a plunger shaft 64 slideable in a bearing lug 65 secured to an internal wall 66 in the valve casing 32, and the shaft 64 extends upwardly out of the casing 32 through a suitable packing gland 67. The lower end of the manually controlled plunger shaft 64 carries a cylindrical piston valve 68, which is engageable with a stop 69 in the form of a collar or flange rigidly fixed to the check valve 70 stem 61, but the valve plunger 64 may move upwardly relative to the check valve 56, and the latter may in turn move downwardly relative to the manually controlled valve 50.

The valve plunger 64 is manually controlled 75

by means of a hand lever 70 pivotally connected by means of a pin 71 to a standard 72 bolted to the top of the valve casing 32 by bolts 73. The hand lever 70 is swingable vertically on the pivot pin 71 and is connected with the upper end of the plunger shaft 64 through a toggle link 74.

When the control lever 70 is raised to the position shown in solid lines in Figure 1, the piston valve 68 is held in the upper portion of the vertical bore 51 above the high pressure supply duct 47, thus preventing the oil from flowing upwardly into the reservoir 41, but providing a path for the oil to flow downwardly through the vertical bore 51. The pressure of the oil forces the check valve 56 to open downwardly against the yielding action of the spring 58 and the oil then flows downwardly through the reducer fitting 54 into the delivery conduit 55 leading to the lifting cylinder.

By moving the handle 70 downwardly, the piston valve 68 is moved downwardly in the vertical bore 51 into the lower portion of the latter below the supply duct 47. This opens the upper portion of the vertical bore 51 above the supply duct 47, and since the plunger shaft 64 is smaller in diameter than the diameter of the bore 51, the oil readily flows upwardly through the latter into the reservoir 41, thus relieving the pressure in the supply duct 47. This causes the spring 58 to close the check valve 56, locking the oil in the delivery conduit 55, but by forcing the plunger shaft 64 downwardly still further, the piston valve 68 engages the stop 69 on the check valve stem 61 and further downward movement of the handle 70 forces the check valve 56 open, thus allowing the trapped oil in the power lift cylinder and the delivery conduit 55 to escape upwardly past the check valve 56, but since the piston valve 68 in this position blocks the vertical bore 51, as indicated in dotted lines in Figure 1, the oil must follow a by-pass, the upper and lower ports of which are indicated by reference numerals 75, 76, respectively.

Inasmuch as the governor shaft 9 runs at a more or less constant speed, the oil is delivered to the supply duct 47 at a substantially constant rate. Therefore, whenever the oil is not being conducted to the cylinder to lift the load, it must be conducted back to the reservoir 41. Ordinarily, this is accomplished by leaving the handle 70 in its lower position as indicated in dotted lines in Figure 1, in which the piston valve 68 is in a lower position below the supply duct 47, thereby permitting the oil to flow upwardly through the bore 51 into the reservoir 41. However, if the handle 70 is left in raised position and the piston reaches its extremity of travel in the cylinder, the pressure rises rapidly in the supply duct 47 and would cause damage if not relieved. Such relief is provided by a suitable relief valve mechanism, indicated in its entirety by reference numeral 77 connected to a vertical passage 78, which communicates with the supply duct 47. This mechanism, which includes a conventional spring loaded pressure relief valve, can be of any conventional construction, and is shown in detail in my co-pending application, and it is therefore considered unnecessary to describe the same herein in detail, as it forms no important part of the present invention.

The reservoir 41 is provided with a vent in order to insure that the pressure within the reservoir does not rise and fall and thus interfere with movements of the control handle 70. This vent is in the form of a short duct 80 extending up-

wardly through the top of the valve casing 32 from the reservoir 41. This short duct 80 is disposed in a boss 81 providing a horizontal surface 82 on which the supporting standard 72 for the handle 70 is mounted. A second duct 83 extends downwardly from the horizontal surface 82 through the flat wing portion 31 and communicates at its lower end with an opening 84 disposed in register with an aperture in the drive or governor housing 6. The ducts 80, 83 in the reservoir and wing portion of the valve casing, respectively, are interconnected by a groove 87 formed in the bottom of the supporting standard 72.

Thus, whenever a slight pressure tends to build up within the reservoir 41, it is exhausted through the duct 80, groove 81, duct 83, and opening 84, into the governor housing 6. The reason for venting the reservoir 41 into the governor housing, rather than directly to the atmosphere, is that usually there is oil vapor in the reservoir 41, which would escape and condense on the outside of the casing 32. By venting this oil vapor into the governor housing, the oil can condense and drop into the oil supply within the housing, without harm.

The oil within the reservoir 41 can be replenished through a suitable hole 90, closed by a plug 91. Access to the valve mechanism is obtained by removing a plate 92 secured by bolts 93.

I claim:

1. In hydraulic mechanism, a control casing having valve mechanism therein and a vent opening in the upper portion thereof, pumping means for supplying fluid to said valve mechanism, drive mechanism for said pumping means, a drive housing for said drive mechanism, bolt means for rigidly securing said casing to said drive housing, said casing having a passage formed therein extending from the upper portion of said casing adjacent said vent opening but spaced therefrom and adapted to register at the opposite end with an aperture in said drive housing, and a part detachably secured to said upper portion of the casing and having a duct formed therein interconnecting said passage and said vent opening.

2. In combination, a governor housing, a removable end plate secured thereto and having an aperture therein, a governor shaft in said housing and extending through said aperture, bearing means in said end plate in which said shaft is journaled, a hydraulic control casing having an associated pump housing attached thereto, means for securing said control casing and said pump housing to said end plate, means in said control casing for controlling the flow of hydraulic fluid to and from said casing, and pumping means in said pump housing for supplying fluid to said control casing and adapted to engage the outer end of said governor shaft to be driven thereby.

3. In combination, a governor housing, an end plate detachably secured thereto, a governor shaft in said housing, bearing means supported on said end plate in which said shaft is journaled, said shaft extending outwardly through a suitable aperture in said end plate, a pair of intermeshing pump gears, one of said gears being mounted on the outer end of said governor shaft, the other being mounted on a supporting shaft, a valve mechanism for controlling the flow of fluid from said pump gears, a control casing for said mechanism having a portion lying against one side of said gears and serving as a housing wall therefor, there being supply and discharge ducts in

said portion serving said pump gears, said end plate serving as the opposite housing wall for the gears, each of said housing walls having a recess to receive one end of said gear supporting

5 shaft, an annular housing member disposed between said governor housing and said control casing and having an opening adapted to receive said gears, and bolts for clamping said end plate, said annular housing, and said control casing rigidly together.

4. In hydraulic mechanism, a drive housing, an end plate therefor, a drive shaft in said housing extending outwardly through an aperture in said end plate and supported for rotation therein, a

15 pump housing disposed in juxtaposition to said end plate, pumping means in said pump housing and attached to said drive shaft to receive power therefrom, said pump housing having intake and discharge means serving said pump means, a control casing having a flat wing portion adapted to lie in juxtaposition to said pump housing and having inlet and discharge passages in register with said intake and discharge means, valve mechanism in said casing for controlling the fluid output from said pumping means, and means for clamping said end plate, said pump housing and said control casing rigidly together.

5. In hydraulic mechanism, a drive housing, an end plate therefor, a drive shaft in said housing extending outwardly through an aperture in said end plate and supported for rotation therein, a

30 pump housing disposed in juxtaposition to said end plate, pumping means in said pump housing and attached to said drive shaft to receive power therefrom, said pump housing having intake and discharge means serving said pump means, a control casing including a fluid reservoir disposed along a side of said drive housing and having a

35 flat wing portion projecting from a wall thereof and adapted to lie in juxtaposition to said pump housing and having inlet and discharge passages in register with said intake and discharge means, valve mechanism in said casing for controlling the flow of fluid in said passages, and means for

40 clamping said end plate, said pump housing and said control casing rigidly together.

45 6. In hydraulic mechanism, a drive housing, a drive shaft therein, a pump housing disposed in juxtaposition to said drive housing and having pumping mechanism connected to said drive shaft and inlet and discharge ports, a control casing having a portion lying in juxtaposition to said pump housing and having inlet and discharge passages disposed in register with said housing ports, valve means in said casing for controlling the flow of fluid in said passages, said casing also including a reservoir connected with said inlet passage and a vent passage connected with the upper portion of said reservoir and communicating with said drive housing.

50 7. In hydraulic mechanism, a drive housing, an end plate therefor, a drive shaft in said housing extending outwardly through an aperture in said end plate and supported for rotation therein, a pump housing disposed in juxtaposition to said end plate, pumping means in said pump housing and attached to said drive shaft to receive power therefrom, said pump housing having intake and discharge means serving said pump means, valve mechanism for controlling the flow of fluid from said pumping means, a valve casing for said valve mechanism including a reservoir portion disposed along a side of said drive housing and having a flat wing portion

55 70 75 projecting from a wall thereof and adapted to

lie in juxtaposition to said pump housing and having intake and discharge passages in register with said intake and discharge means and connected with said reservoir and said valve mechanism within said casing, and a vent passage leading from the upper portion of said reservoir portion through said flat wing portion, the latter having an opening disposed in register with an aperture in said drive housing, and means for clamping said casing and said pump housing rigidly to said end plate.

8. In hydraulic mechanism, a valve casing having valve mechanism and a reservoir therein for hydraulic fluid, the flow of which is controlled by said mechanism, said casing also having a vent opening in the upper portion thereof for maintaining the pressure in said casing at substantially atmospheric to prevent pressure interference with said valve mechanism, a supporting structure having a fluid receiving chamber therein, a portion of said casing being adapted to be secured to said supporting structure, and duct means connecting said vent opening with said casing portion and adapted to register with an aperture in said supporting structure to conduct any vapor from said fluid to said chamber.

9. In hydraulic mechanism, a valve casing having valve mechanism and a reservoir therein for hydraulic fluid, pumping means for supplying a flow of fluid to said valve mechanism to be controlled thereby, said casing also having a vent opening in the upper portion thereof for maintaining the pressure in said casing at substan-

tially atmospheric to prevent interference with said valve mechanism, a housing, drive means in said housing for driving said pumping means, an extension on said casing, bolt means for rigidly securing said casing extension to said housing, said extension having duct means extending from the upper portion of said reservoir adjacent said vent opening and adapted to register at the opposite end with an aperture in said housing, and a part secured to said upper portion of the reservoir and having a duct formed therein interconnecting said duct means and said vent opening to equalize the pressure inside and outside the reservoir to avoid pressure interference with said valve mechanism while conducting any vapor from said fluid to collect the condensate thereof in said housing.
